STRINGED MUSICAL INSTRUMENT

Walter J. Pelensky, 19C Manheim Gardens,
Philadelphia, Pa. 19144

Filed May 6, 1969, Ser. No. 17,032

Term of patent 14 years

Int. Cl. D17—03

U.S. Cl. D56—1

Fig. 1

Fig. 3

Fig. 2

Fig. 4

FIG. 1 is a perspective view of a stringed musical instrument, specifically a Ukrainian Kobza, showing my new design;

FIG. 2 is a face view;

FIG. 3 is a left side elevational view; and

FIG. 4 is a right side elevational view thereof.

I claim:

The ornamental design for a stringed musical instrument, as shown.
